UNITED STATES PATENT OFFICE

1,988,547

TUBE FORMING APPARATUS

William H. Engelbertz, Pittsburgh, Pa.

Application March 17, 1933, Serial No. 661,227

5 Claims. (Cl. 29—33)

This invention has reference to improvements in tube rolling or drawing apparatus, which, for reason of brevity, will be referred to as tube forming apparatus hereafter, wherein a cup-shaped, thick-walled, hollow billet, carried by the front end of a mandrel, is being forced through a succession of roll passes or through any kind of suitable dies, which for brevity will be referred to hereafter as dies, which gradually 10 reduce the wall-thickness of the billet, thus elongating it over the mandrel, whereby a tube with one closed end is being formed. Suitable means then separate tube and mandrel after the tube has been loosened somewhat on the mandrel, which may be accomplished, for instance, by passing cross-rolls, whereupon the mandrel is brought back to its initial position for re-use, while the tube receives further treatment depending on its final destination.

20 The principal object of this invention is, generally stated, to provide an apparatus of the kind referred to above, more effective and efficient than any kind practiced in this art at present. These advantages will be effected by:

25 1. Abolition of waste of time and power;
2. Elimination of manual labor;
3. Decrease of production costs and increase of output rate. These will be achieved by cooperating means to supply the mandrel, to place it 30 into operating position, to guide said mandrel while forcing the billet through the dies, and to return the mandrel, after being freed from the tube, to its initial position for further use. Start and duration of all mandrel movements 35 are timed, in accordance with the invention.

Further, the separation of tube and mandrel, after the hold of the tube on the mandrel has 40 been loosened, will be performed by automatic means and without changing the direction of the mandrel, thus making said separation a time and energy saving procedure which preserves the heat of the tube, thereby permitting further hot-treatment of the latter, such as passing a reducing or sinking mill without reheating.

45 Another achievement of the invention is a combined mandrel-locking-and-guiding device operated by the incoming mandrel itself when moving into operating position; thus, an upset or buckling of the mandrel during the tube-forming operation will be prevented.

A further achievement of the present invention concerns the security of the whole apparatus against damage. While the advance and reverse stroke of the ram, which will be described later, 50 is being checked by well known electrical appli-

ances, previously there was the possibility of starting, i. e. re-advancing, said ram before a new mandrel or billet had been brought into operating position. This danger is eliminated by the invention, in providing means which automatically interrupt the power supply of the ram-drive temporarily, until mandrel and billet occupy their pre-commencing position and thereby restore the power supply and start the tube-forming operation automatically.

5 10 A still further achievement of the invention is the automatic control of all movements of the tube-forming apparatus by cooperation of the various devices, comprising said apparatus.

All advantages comprehended by this invention will be described more fully hereinafter, and will be particularly pointed out in the appended claims. To enable those skilled in the art to readily comprehend and practice this invention, reference should be made to the accompanying 15 drawings. Of course, I wish to have it understood that it is not my intention to confine or limit myself to any specific details of construction described or illustrated herein, since changes and alterations will readily suggest themselves to 20 those skilled in this art without departing from the spirit and scope of the invention.

25 The accompanying drawings show one preferred embodiment of the invention in somewhat diagrammatical form in which—

30 Fig. 1 is a plan view of the main part of the apparatus;

35 Fig. 2 is a diagrammatical side elevation thereof, with the tube-forming operation just completed;

40 Fig. 3 is an enlarged side elevation of the mandrel kick-out device, taken on line A—A of Fig. 6;

45 Fig. 4 is an enlarged side elevation of another mandrel kick-out device, taken on line B—B of Fig. 1;

50 Fig. 5 is an enlarged side elevation of the billet receiving table and means to open and close a safety switch, taken on line C—C of Fig. 1;

55 Fig. 6 is the continuation of Fig. 1;

Fig. 7 is a front elevation of the mandrel and tube separating device in its pre-acting position;

Fig. 8 is the same as Fig. 7, but with the separation of mandrel and tube commencing;

Fig. 9 is a fragmentary side elevation of the tube and mandrel separating device;

Fig. 10 is a fragmentary front elevation of the starting means for the mandrel and tube separating device, in rest position;

Fig. 11 is one of the tube advancing rollers, 55

as part of the separating device, in enlarged scale;

Fig. 12 is an enlarged vertical cross section of the mandrel supplying device;

5 Fig. 13 is the same as Fig. 12, showing the incoming mandrel;

Fig. 14 is the same as Figs. 12 and 13, showing the locked mandrel in operating position;

10 Fig. 15 is an enlarged cross section of the mandrel-bar bearing-, locking-, and guiding means;

15 Fig. 16 is a fragmentary enlarged view, indicating in a somewhat diagrammatic way the relative position of two levers keyed to one shaft, as part of Figs. 12, 13, 14;

Fig. 17 is a fragmentary enlarged partial section of the mandrel bearing, with the mandrel in place.

20 The operation of the apparatus will be performed as follows: Referring to Fig. 1, after mandrel 1 has been brought into alignment with the ram consisting of mandrel-bar 2 and rack 3, billet 4 will be placed on table 5 located between said mandrel and dies 6, 7, 8, 9, the forward movement of ram-rack 3, driven by pinion 10 which in turn receives its power from motor 11 over gear reduction unit 12, commences and forces said billet through said dies; thereby transforming billet 4 into a tube 13, as shown by Fig. 2.

25 Power is supplied to motor 11, which is of the D. C. type, from a motor generator set because the operating speed of the tube-forming apparatus shall be adjustable over a wide range.

30 Current may be supplied to motor 14 from any suitable source by wires 16, while other wires 17 may be arranged to supply current to the ram-driving motor 11 for the purpose of exciting its field. The driving power for motor 11 may be transmitted by wires 18 connecting the generator 15 with said motor. No attempt has been made in the drawings to specifically indicate the control means and requisite wiring connecting the various units, as the details thereof form no part of the present invention and, are well understood by those familiar with this method of controlling the operation of a direct-current motor through a motor-generator set which is commercially known as the "Ward-Leonard" principle or system of control.

35 The operation of the tube-forming apparatus is arranged so that motor 11 will start and accelerate the ram and force it, with mandrel 1 and billet 4 in front, through the passes of dies 6, 7, 8, 9 at a predetermined speed, reverse, and return the ram to its initial position. Mandrel 1 and tube 13 however, as practically one unit, proceed in forward direction by means of rollers 19 and pass a pair of cross-rolls 20 whereby tube 13 is loosened on mandrel 1.

40 With the above preliminary understanding of the tube-forming process itself, including the loosening of the tube on the mandrel, both of which have absolutely no bearing upon the present invention, the various cooperating devices, embodying the invention, which now shall be described, will readily be understood.

45 Figs. 6, 7, 8 and 10 show the automatically acting tube-stripping and mandrel - kickout means. After passing the cross-rolls 20, mandrel 1 and the still adhering tube 13, advanced by rollers 21, turn lever 22 about its pivoting point 23, thereby operating the starting switch 24 by shifting lever 25 of said switch through 50 the medium of pivoting lever 26. Thus, the

55 electric circuit between wires 27, 28 will be closed, whereby electric solenoid 29 comes into action. This solenoid has a fourfold purpose at a time, namely, to give tube 13 free passage, to arrest mandrel 1, to adjust idler rollers 30 so as to cooperate with rollers 21, and to advance tube 13 in forward direction "D". Fig. 7 shows the mandrel and tube stripping means in the resting stage, while Fig. 8 shows the same means in working position. Rod 31 of solenoid 29, being 10 connected with, and raising levers 32, 33 about their pivots 34, 35, shown by Fig. 8, thereby raises the fork-shaped plate 36, by connecting means 37, 38, 39, over pivot 40, which keeps mandrel 1 in a stationary position and, on the other hand, lowers mandrel and tube stopping means 41, 42, 43, and means 44, 45, 46, the last three in the order stated, to put idler rollers 30 into action for the purpose of advancing tube 13. Each of said rollers is supported by a fork-shaped piece 47, bearing on spring 48 in a cage 49 with lid 50 on top, shown in enlarged scale by Fig. 11. Idler rollers 30 are connected by cross-bars 46, as indicated by Figs. 7 and 8. Cages 49 may have a fixed position and may be 25 carried by structural means 51, shown in dot-and-dash lines by Fig. 9 which is a fragmentary transverse view of Fig. 8.

55 Fig. 6 shows tube 13, freed from mandrel 1, advanced by supporting rollers 21, after having 30 turned down lever 52 mounted on shaft 53, thereby automatically operating, at a time, starting switch 54 by shifting lever 55 of said switch through the medium of pivoting lever 56, and switch 57 through the medium of the 35 same kind of lever-system used for switch 54. Thus, the electric circuit between wires 58, 59 will be closed and the mandrel kickout is started by motor 60 over gear reduction unit 61, coupled thereto, and crank-shaft 62. Kickout shaft 63, 40 mounting a plurality of levers 64, is connected with crank-shaft 62 by lever 65 and rod 66. One revolution of crank-shaft 62 effects an "x"-degree turn of levers 64, 65, thus kicking out mandrel 1, whereupon said levers return to their 45 initial position. The function of this commonly known kickout device is clearly indicated by Fig. 3. Also, through the downward turn of lever 52 by the advancing tube 13, switch 57 disconnects wires 27, 27, thereby de-energizing sole- 50 noid 29. Thus, the means, shown by Fig. 8, return into rest position, i. e. the initial position shown by Fig. 7, in order to be ready for the next separating operation. The switches 54, 57 will be returned to their initial position by 55 counter-weight 67, as soon as lever 52 has been released by the passing tube 13. The same action takes place by the medium of counter-weight 68 with regard to switch 24, as soon as lever 22 has been released by mandrel 1, i. e. 60 after the latter has been kicked off the rollers 21. The mandrel then rolls over skids 69 to the conveying rollers 70 which advance said mandrel in direction "DD" (Fig. 6) to the opposite end of the conveyor, as far as indicated in dot-and-dash line by Fig. 1.

65 In Fig. 2, the ram, consisting of mandrel-bar 2 and rack 3, is shown at the end of its forward movement, i. e. in its position after completion of the tube-forming operation. The backward movement of the ram, rack turns lever 71, mounted on shaft 72, the operating the electric starting switch 7 shifting lever 74 of said switch through 75 the medium of lever 75, keyed to shaft 72.

the electric circuit between wires 76, 77 and motor 78 will be closed. Said motor, over the medium of gear reduction unit 79 and crank-shaft 80, effects, at a time, the supply of a 5 fresh cooled mandrel, the ejection of a used hot mandrel from the conveyer rollers 70, and the operation of safety switch 81, to which will be referred hereinafter. Shaft 82, on which a series of levers 83 are mounted, is connected 10 with crank-shaft 80 by lever 84 and rod 85. One revolution of crank-shaft 80 effects a turn of levers 83, 84 to a certain degree, thus lifting and delivering a mandrel 1 from the cooling rack 86 for the following tube-forming operation. 15 Whereupon said levers return to their resting position. The function of this device is the same as for the mandrel kickout, shown partially by Fig. 3. As said before, while a fresh mandrel is being delivered, a used one will be 20 ejected from the rollers 70 to cooling rack 86 at a time. This last step has been illustrated by Figs. 1 and 4. The rotation of shaft 82 in arrow direction results in the upward motion of plates 87, thus pushing mandrel 1 from rollers 70 to 25 cooling rack 86. Shaft 88, carrying levers 89, which in turn are connected with plates 87, and connecting means 90, 91, 92, 93 is the medium used in performing said mandrel movement.

Finally, said rotation of shaft 82 in arrow 30 direction, indicated by Fig. 5, temporarily interrupts the power-supply of the ram-driving motor 11, so that said ram cannot be advanced for the next tube-forming operation unless mandrel 1 and billet 4 are in a position, ready 35 to be advanced, as shown by Fig. 1. This power interruption will be obtained by the automatic operation of safety switch 81 which is disconnected by double lever 94, connected by rod 95 to lever 96, the latter being keyed to shaft 82. 40 While the dot-and-dash lines in Fig. 5 show the levers 94 and 96 in rest position, the heavy lines show said levers in a working stage, i. e. the downward motion of finger 97 of switch 81 has 45 just been completed by lever 94, thereby disconnecting the wires 18, 18, shown by Fig. 1. The downward motion of finger 97 turns double lever 98 about pivot 99, thus bringing said lever into position to receive billet 4, as shown by Fig. 5. The return of shaft 82 to its initial position, caused naturally by the function of crank-shaft 80, results in the return of levers 94 and 50 96 to their rest position. Upon receiving billet 4, double lever 98 is turned down and rests again on table 5, while the upward motion of the 55 other end of said lever pushes finger 97 of contactor 81 back to its initial position, thus reconnecting wires 18, 18, thereby restoring the power-supply for the ram-driving motor 11, and starting the next tube-forming operation automatically. Counter-weight 100, mounted on 60 shaft 72, acts to bring lever 71 and therewith, switch 73 back to their initial position, after said lever has been released by the advancing ram-rack 3.

Figs. 12, 13, 14 illustrate the cooperating means which deliver, receive and lock mandrel 1, and which guide said mandrel advancing in direction "D", shown by Fig. 1, during the tube-forming operation. The mandrel, when lifted 65 from cooling rack 86 by levers 83, indicated by Fig. 12, passes skids 101 and turns down the counterweighted arms 102, mounted on shaft 103, shown by Fig. 13, then rolls into operating position, shown by Fig. 14, and rests on bearings 104, 105, which in turn are carried by housing 70

115. The downward movement of arms 102, referred to before, will form an open gate, shown by Fig. 13, for the incoming mandrel by raising upper guides 106, keyed to shaft 107. The shafts 103 and 107, connected by levers 108, 109, rods 110, 111, and levers 112, 113, the last two keyed to shaft 114, act in unison. 5

Also by the rotation of shaft 103, the locking-pins 115 of upper guides 106 are withdrawn prior to the upward motion of said guides. To assure this, lever 109, keyed to shaft 107, shows a keyway extension, indicated by Figs. 12, 13, 14, and in enlarged scale by Fig. 17. Thus, guide 106 can be raised only after lever 109 has reached about the dotted-line position shown by Fig. 16. As soon as mandrel 1 has passed over arm 102, counterweight 116 re-acts and brings said arm and all other moving parts described before, back to their initial position, with mandrel 1 in place and the upper guides 106 locked 20 by pins 115. Now mandrel 1, when advanced in direction "D" in order to force billet 4 through the passes of dies 6, 7, 8, 9, is prepared to meet the great axial stress imposed upon it during the tube-forming operation, since the provided series 25 of bearings 104, 105, and guides 106 prevent the mandrel from buckling or upsetting. One unit of the mandrel locking means, referred to above, comprises pin 115, spring 117, ball-joint 118, threaded bolt 119 for spring adjustment, and 30 lever 120, keyed to shaft 103.

Figs. 12 to 15, inclusive and Fig. 17, indicate in dot-and-dash lines the mandrel-bar holder 121, mounted on ram-rack 3, which is also shown from another point of view in Figs. 1 and 2. 35 The mandrel-bar 2 is resting on bearings 122, 123, carried by housing 124, as shown by Fig. 15. Said bearings with guides 125, as practically one unit when screwed together with bolt 126, form a locked, that is, rigid, guide for the advancing mandrel-bar during the tube-forming operation. 40

When changing the mandrel-bar 2, that is, when the work program has to be changed to another tube dimension, the nut of bolt 126 45 must be turned back a few threads so that said bolt may be turned aside. After that, guide 125 may be lifted and turned about pivot 128 by means of handle 127, whereupon mandrel-bar 2 can easily be lifted out of the slotted holder 121 50 by an overhead crane. It is obvious that the mandrel-bearings and guides 104, 105, 106, serve as such to mandrel-bar 2 also.

The linings 129, 130, 131, shown by Fig. 17, may be applied to the mandrel-bar bearings and 55 guides 122, 123, 125 as well as to the mandrel bearings and guides 104, 105, 106, in order to prevent said bearings and guides from wearing out. On the other hand, such linings, with a finger-like extension, keyed to the respective 60 guides and bearings, as shown for example by Fig. 17, may have a varying bore, in order to be suitable for a wide range of mandrel and mandrel-bar diameters, in fact for all mandrels and mandrel-bars required by the working 65 schedule of the tube-forming apparatus.

Instead of using electric switches and their auxiliary equipment as specified and shown in the drawings, any kind of modern electrical appliances, for instance, automatically acting 70 photoelectric relays, may be utilized in accordance with the invention.

This invention shall not be limited to the control of all mandrel movements in the tube-forming apparatus but does include automatic 75

control of the start, forward stroke, and reverse (not shown on the drawings) of the ram, consisting of mandrel-bar 2 and rack 3, thus making it practically impossible for the ram to overrun in either direction.

- The foregoing description of the method of operating the tube-forming apparatus has disclosed how the various devices are acting in unison so that one movement automatically starts the succeeding one, after a billet 4 has been placed upon table 5. Thus, in fact, the automatic control of all operations of the tube-forming apparatus, including mandrel-handling, will be achieved by this invention.
- 15 A considerable reduction in operation costs by abolition of waste in energy and time, obtained by most economical power consumption and elimination of manual labor, and the increase in production by speeding-up and timing of all 20 mandrel movements in order to preserve the heat of the tube so as to permit the tube to pass a reducing- or sinking-mill without reheating, are the beneficial effects of this invention.

What I claim is:

- 25 1. In a tube forming apparatus, a push bench comprising, a series of dies, a mandrel for a cupped billet, a ram connected to the mandrel and means for reciprocating the ram for advancing said mandrel with billet towards, and through, the dies at a predetermined speed whereby the billet is formed into a tube over the mandrel, and for moving the ram backwardly to its initial position at a higher rate of speed, comprising a motor, means connecting the ram and the motor whereby rotation of the motor in a predetermined direction is operative to impart movement to the ram in a corresponding predetermined direction, a generator, means for driving the generator, connections between the generator and the motor, control means operative to vary the output voltage delivered to the motor from the generator whereby the ram may be moved to and from the dies at desired speeds by varying said voltage, a safety switch, means connecting said switch with the ram-driving motor, means connecting said switch with the generator, mandrel-supplying means for timed placement of a mandrel into working position, automatically acting means connected to the mandrel-supplying means for operating said switch when a mandrel is placed into working position causing disconnection of the ram-driving motor and the generator whereby the backward motion of the ram comes to an end, billet-receiving means for holding a cupped billet in alignment with the mandrel and the dies, automatically acting means connected to the billet-receiving means, for operating said switch when a cup-shaped billet to be formed into a tube has properly been placed causing reconnection of the ram-driving motor and the generator whereby the free moving action of the ram is restored, and the tube-forming operation is started, simultaneously.
- 60 2. In apparatus according to claim 1, means for expanding the diameter of the tube formed over the mandrel to loosen the hold of the tube on the mandrel, a shiftable stop for halting the advancing tube with the mandrel inside, means for conveying the tube with the mandrel from the tube expanding means to said stop, a solenoid, cooperating means separately connected with the solenoid comprising a shiftable mandrel gripper, a plurality of adjustable rollers, and said shiftable stop, means connected with the sole-
- 70

noid and extending into the path of tube and mandrel causing action of said solenoid when the tube and mandrel reach said shiftable stop whereby the solenoid is operative to impart relative movement to said shiftable stop, shiftable mandrel gripper, and adjustable rollers, simultaneously, thus effecting the arrest of the mandrel and stripping of the tube from the mandrel, means for further advancing the tube, a switch, means connected with the switch and extending into the path of the advancing tube causing the start of said switch by said tube and effecting de-energization of said solenoid whereby said rollers, gripper, and stop return into rest position, mandrel kick-off means, a mandrel kick-off drive, and operatively connecting means between the kick-off drive and the kick-off means, a motor for said drive, a switch started simultaneously with the first-mentioned switch by said tube by means connected with the switch and extending into the path of the advancing tube, means connecting the second-mentioned switch and the motor whereby the action of said switch is operative to impart relative movement to the mandrel kick-off drive and the mandrel kick-off means effecting expulsion of the used mandrel from its supporting means, a transfer table so positioned as to receive the ejected mandrel, conveying means so located as to receive the mandrel from the transfer table and to advance the mandrel towards its initial position for re-use.

3. In a tube forming apparatus, a push bench comprising, a series of dies, a mandrel for a cupped billet, a ram connected to the mandrel, means for reciprocating the ram for advancing said mandrel with billet towards, and through, the dies at a predetermined speed whereby the billet is formed into a tube over the mandrel, and for moving the ram backwardly to its initial position at a high rate of speed, comprising a ram-driving motor cooperating with a generator, control means automatically started by the advancing ram and adapted to stop the forward motion of said ram after the completion of the tube-forming operation, and to reverse the polarity of the field of the generator whereby the direction of rotation of the ram-driving motor is operative to impart movement to the ram in a corresponding predetermined direction and speed so as to move said ram back towards its initial position, mandrel-handling means, a drive for operating the mandrel-handling means, a motor for said drive, means connecting said drive with the mandrel-handling means, a switch, means connecting the switch with the motor of said drive, mandrel cooling means and means connected to said switch and extending into the path of the ram on its way to the initial position whereby said ram acts upon the last-mentioned means and said switch to cause relative movement of said drive and said mandrel-handling means, thus effecting the kick-up of a used mandrel onto said mandrel cooling means, and timed delivery of a cooled mandrel for the next tube-forming operation, so as to have the last-mentioned mandrel placed in proper working position, and said ram back in its initial position, simultaneously.

4. In a tube forming apparatus, a push bench comprising, a series of dies, a mandrel for a cupped billet, a ram carrying a mandrel-bar rigidly connected to the ram and detachably connected to the mandrel stationary mandrel-bar receiving and guiding means consisting of a

desired number of lockable chambers, means for reciprocating the ram for advancing said mandrel with billet towards, and through, the dies at a predetermined speed whereby the billet is 5 formed into a tube over the mandrel, and for moving the ram backwardly to its initial position at a high rate of speed, comprising a ram-driving motor cooperating with a generator, control means automatically started by the advancing ram and adapted to stop the forward 10 motion of said ram after the completion of the tube-forming operation, and to reverse the polarity of the field of the generator whereby the direction of rotation of the ram-driving motor 15 is operative to impart movement to the ram in a corresponding predetermined direction and speed so as to move said ram back towards its initial position, mandrel-handling means comprising, a kick-up adapted to pick up one used mandrel at a time, a table constructed to take 20 over, to cool and to move, said mandrel towards its working position, and a kick-off of suitable design to deliver one cooled mandrel at a time for the tube-forming operation, a drive for operating the mandrel-handling means, means connecting said drive with the mandrel-handling means, mandrel receiving and guiding means comprising a desired number of locked chambers spaced to each other and in alinement with 25 the tube-forming dies, means operated by said cooled mandrel while moving into working position to open said locked chambers for admitting said mandrel, and automatic means for relocking said chambers after said mandrel oc-

cupies its working position therein, whereby said chambers form a guide for said mandrel and mandrel-bar during the tube-forming operation.

5. In tube-forming apparatus including a push bench having a bed carrying a plurality of mandrel- and mandrel-bar supports spaced to each other in alinement with the tube-forming dies, a plurality of pivoted levers having their pivoting point fixed on the mandrel- and mandrel-bar supports, means to lock the free end of the 10 levers to the mandrel- and mandrel-bar supports; means for conveying a mandrel to the mandrel-supports and means actuated by the mandrel while being so conveyed, to unlock and to turn aside a number of said levers to permit 15 the mandrel to occupy its working position upon the supports, and to turn back and to relock the levers to the mandrel-supports, thus having the levers and the mandrel-supports act in unison to form a series of guides for the mandrel 20 during the tube-forming operation; means to unlock and to turn aside the remaining number of the first-mentioned levers to permit the mandrel-bar to be placed into working position upon the supports, means to turn back and to relock 25 the levers to the mandrel-bar supports, thus having the levers and the mandrel-bar supports act in unison to form a series of guides for the mandrel-bar during the tube-forming operation; interchangeable linings, attached to the levers 30 and to the mandrel- and mandrel-bar supports, to form passes for the mandrel and mandrel-bar during the tube-forming operation.

WILLIAM H. ENGELBERTZ.
